SANITARY NAPKIN

George Walter Lindsey, Rockville Center, N. Y.,
assignor of one-fourth to Charles R. Landon,
Ozone Park, N. Y.

Application January 8, 1934, Serial No. 705,644

1 Claim. (Cl. 128—290)

My invention relates to an improvement in a sanitary napkin and its novelty lies in the combination, adaptation, and arrangement of parts as will be more fully hereinafter pointed out.

5 Most of the sanitary napkins now used by women are made of cellulose and are very absorbent but the middle portion of these napkins fill up with the menstrual flow and this rapidly soaks through in the central portion and goes

10 through the bottom and also travels to the unprotected edges and so spots the underwear and other garments.

My device solves this problem, furnishing a napkin that is protected against soaking through the bottom by an overlapping or double moisture repellent member and also protected by an overlapping double protection on its edges so that it cannot spot or stain the clothing of the wearer either through the bottom or sides particularly

20 of the middle portion and yet is so constructed that the entire napkin is disposable through the toilet hopper into the sewer.

Referring to the drawing, Figure 1 is a top plan view of the preferred form of my device having a portion broken away and one end folded back in fastening position.

Figure 2 is a side elevation of Figure 1.

Figure 3 is a top plan view of another form of my device.

30 Figure 4 is a cross section on the line 4—4 of Figure 1.

Figure 5 is a cross section on the line 5—5 of Figure 1.

Figure 6 is a top plan view of the moisture repellent wrapper as shown in Figure 1 with the outer portion broken away for convenience in illustration.

Figure 7 is a top plan view of the moisture repellent wrapper as shown in Figure 3 with the outer portion broken away for convenience in illustration.

In the drawing 10 is the central pad preferably made of a plurality of layers of cellulose material over which a chemically treated moisture repellent wrapper 11 is adapted to be folded so as to lay over the top of the pad 10 and come down around the side edges 40 and fold over the bottom of the pad 10 so as to overlap one edge 21 of the wrapper 11 over the other edge 22 on said bottom and then secured (or not, as preferred) together at 23 with a light adhesive. The overlapping edges 21 and 22 may preferably extend across the full width of the pad 10 so as to form a complete wrapper 11 of double thickness over the entire bottom of said pad 10. In the preferred

form of my device shown in Figure 1 the wrapper 11 is cut on the lines 12, 13, 14, 15 and 16 and the side flaps 17 and 18 formed thereby are turned back on the folds 19 and 20 respectively to form the turn back flaps 17 and 18 and thereby provide double side wall protection to the central pad 10. Also the end flaps 24 and 25 are turned back on the lines or edges 26 and 27 to form end flaps 24 and 25 and thereby strengthen the edges 26 and 27 against possible tearing. This construction is clearly shown in Figures 1, 2, 4, 5, and 6 and an opening 35 is thereby formed in the top of said chemically treated moisture repellent wrapper 11.

A second form of my device is shown in Figures 15 3 and 7 in which the moisture repellent wrapper 11 is cut along lines 28, 29 and 30 so as to form flaps 31 and 32 which are adapted to be folded back along lines 33 and 34 respectively thereby effecting the desired opening 35 in the moisture 20 repellent wrapper 11 and furnishing a double side wall moisture repellent construction over the side edges of the central pad 10.

A piece of light weight gauze 36 is adapted to be folded around the top of the combined central 25 pad 10 and moisture repellent wrapper 11 as described in both forms as shown in Figures 1 and 3 so as to overlap at 37 along the central portion of the bottom of the same. The use of the gauze 36 entirely enclosing the central pad 10 and the 30 chemically treated moisture repellent wrapper 11 as it draws at each end tends to fold in the corners of the wrapper 11 thereby forming rolled corners 38.

The ends of the chemically treated wrapper 11 35 are adapted to project beyond the ends of the central pad 10 and thereby form with the ends of the gauze 36 a combined roll or fold 39 at each end for pinning or fastening the napkin at each end 39 to a belt or other supporting means in 40 position for use.

The wrapper 11 so encases the central pad 10 with an opening 35 on the top side in both the structures of Figures 1 and 3 that it thereby presents this open portion 35 for the menstrual 45 flow or other usual use as worn next to the vaginal opening of the user.

The wrapper 11 must be chemically treated in a way to make it soft and pliable and non-injurious in use and also make it moisture repellent so as to 50 be effective as described in its use herein. Applicant makes use of a chemical treatment for securing this result, which treatment involving the use of trichlorethylene as a solvent with a fatty acid such as stearic acid is independent of 55

the invention described and claimed herein but which has been found by actual test to be effective in securing the required results, and harmless in use.

- 5 The device also furnishes a napkin that will hold a much greater quantity of menstrual flow as the chemically treated moisture repellent wrapper 11 will prevent soaking through the pad 10 in its central portion because the edges 21 and 10 22 are sufficiently overlapped to form a double thickness and the consequent passing off of such excess. This will thereby compel the excess liquid to saturate beyond the central portion and 15 toward and into the end portions of the pad 10 which portions are not utilized in the prior art. These end portions of the pad 10 have not been used heretofore in the prior art because of the soaking through in the central portion and consequent passing off of such excess in the staining 20 of the underwear and therefore these end portions actually come into use for the first time because of the overlapping of the edges 21 and 22 of the moisture repellent wrapper 11 on the bot-

tom which holds the excess moisture and thereby compels it to travel by absorption into the end portions of the pad 10.

The chemically treated moisture repellent wrapper 11 may be used in one or more thicknesses as may be found desirable in order to insure the required strength but in the devices illustrated only one thickness is shown as that has been found practical in actual use.

5 It will be apparent that many variations may be 10 made in the details of my device without departing from the spirit and intent of the same.

I claim:

In a sanitary napkin a central pad of cellulose, a 15 wrapper of chemically treated moisture repellent cellulose encasing said pad and overlapping at the bottom so as to form a double thickness thereover and having an opening in the upper face at its central portion with turn back elements forming a double thickness over the side edges of the 20 central pad and a piece of gauze folded thereover so as to form fastening tabs at each end.

GEORGE WALTER LINDSEY.
